UNITED STATES PATENT OFFICE

ISAAC C. DECKER, OF MONTGOMERY, PENNSYLVANIA

CHAIR

Application filed July 6, 1929. Serial No. 376,436.

This invention relates to chairs, especially those of the reclining type in which the back may be adjusted with reference to a stationary seat.

5 It is a particular object of the invention to provide a construction in which the chair back automatically accommodates itself to any desired position of the occupant's body. Use is made of an improved friction device 10 which is operated in part by the weight of the occupant's body and serves to effectively maintain the back in any adjusted position. Means are provided for automatically returning the back to its normal sitting position, 15 when the chair is unoccupied.

A further object is the utilization of resilient means to augment the operation of the friction retaining device for the back. For this purpose, it is proposed to make use of 20 the usual upholstery springs which serve to support the chair seat.

It is intended to provide operating mechanism for the chair back which not only is of very simple construction, but in the main includes certain parts used in chairs of conventional character. The cost of manufacture 25 is thereby materially reduced.

Further objects of the invention will appear from the detailed description given 30 hereinafter.

Reference is now had to the accompanying drawings, wherein there is shown a practical embodiment of the invention and in which:

Fig. 1 is a side elevation of my improved 35 chair with the parts in their normal or sitting position, certain portions of the chair being broken away to show the details of construction;

Fig. 2, a similar view showing the positions of the parts when the chair back is in 40 reclining position;

Fig. 3, a horizontal sectional view, looking 45 upwardly, taken on line 3-3 of Fig. 2;

Fig. 4, a vertical section taken on line 4-4 50 of Fig. 2;

Fig. 5, a fragmentary vertical section taken 55 on line 5-5 of Fig. 1 and showing one of the pivotal connections between the seat frame and the chair frame; and

Fig. 6, a fragmentary, perspective view of 60

one of the lower corners of the chair back.

The chair comprises a base or frame 1 having the usual legs 2 and arms 3. This frame is made up of suitably connected side boards 4, 5 and end boards 6, 7. Thus, a rigid framework is provided to support the other parts of the chair and the mechanism which permits adjustment of the chair back relative to the seat.

Suitably secured about its edges to frame 1 and covering the top of the frame is a flexible cushion seat 8. The seat is made up of the usual inner fabric lining 9, stuffing 10, and outer fabric covering 11. The seat is generally tufted, as indicated.

Mounted inside of frame-work 1 beneath seat 8 is a bottom or seat frame 12. This seat frame is made up of two series of longitudinal and transverse members 13, 14 suitably secured together at their points of intersection. The rigid seat frame thus provided is pivotally mounted at its forward corners on a pair of brackets 15, 15 screwed or otherwise secured on the inner faces of chair frame 1 (see Fig. 1). While these brackets provide a satisfactory means for pivotally mounting the seat frame in the chair frame, any suitable form of pivotal mounting may be used.

The details of one of the brackets is shown in Fig. 5. It is L-shaped and made of metal. Near its outer extremity the bracket is provided with a struck-up portion 16 having a central opening 17. A screw, or the like, 18 extends upwardly through opening 17 and is secured in the under side of the corresponding longitudinal member 13 of the seat frame. A washer 19 is located between the head of the screw and bracket 15.

The screws 18 on either side of seat frame 12 are not screwed up tight, as shown in Fig. 5. This permits vertical swinging movement of the rear free end of seat frame 12 during operation of the adjustable chair back, as will appear later.

Located between seat frame 12 and the under side of the cushion seat 8 is a series of coil springs 20. These springs rest on seat frame 12 and serve in the usual manner to support the upholstered seat portion well above the upper surface of the chair frame 1.

Springs 20 are suitably secured, as by staples 21, to the transverse members 14 of the seat frame.

There is a groove or depression 22 on the under face of each of members 13, 13 of the seat frame near the rear extremity thereof. The purpose of these will appear later.

Pivotedly mounted in chair frame 1 is a back 23. The back is upholstered in the usual manner, as indicated at 24. The upholstery is applied to a frame-work, which includes a pair of side members 25, 26 and a lower cross member 27. The back is pivotally mounted intermediate its ends on a rod 28 which extends through suitable openings in side members 25, 26 and is removably supported at its outer extremities in the chair frame 1. Rod 28 may be removed by driving it through these openings, when it is desired to disassemble the chair.

On each of the lower extremities of the back frame members 25, 26 there is mounted a metal bracket 29. Each of these brackets has a bent up portion 30 to the outer extremity of which is riveted or otherwise suitably secured one of the flattened and perforated ends of a cross member or tube 31. As shown in Fig. 1, tube 31 supports the rear, free end of seat frame 12. The seat frame, it will be noted, extends above cross member 31 and between the lower extremities of the side members 25, 26 of the back. Normally, the parts are disposed in the sitting position shown in Fig. 1. At this time, cross member or tube 31 engages with the pair of depressions or recesses 22, 22 on the under side of seat frame 12. The parts are held in this position by a coil spring 32, one end of which is attached to tube 31 and the other end to the end board 7 of the chair frame.

The lower portions of the side members 25, 26 of the chair back are each cut away at 33, so as to provide a stop surface 34 which normally engages with end board 7 of the chair frame and thus limits the forward swinging movement of the back. Each of the same members also has an inclined stop surface 35 which, as shown in Fig. 2, limits the rearward swinging movement of the back by engaging with the upper edge of end board 7.

Operation.—As stated, when the movable parts of the chair are in the positions shown in Fig. 1, i. e., the sitting position, tube 31 is in engagement with the grooves 22, 22 on the under side of the seat frame. Since the upholstery springs 20 are placed in position under compression, the action of these springs will cooperate with the weight of the free end of seat frame 12 to force the latter into close frictional engagement with the upper surface of cross member 31.

The arrangement of brackets 15, 15 on which the seat frame 12 is pivoted and rod 28 on which the back is pivoted, is such that, when the back is swung rearwardly, cross

member 31 serves to pry up or elevate the rear end of bottom frame 12 and at the same time slides along in close frictional contact with the under surface of members 13, 13. Inasmuch as any elevation of seat frame 12 operates in opposition to the upholstery springs 20, there is produced a considerable frictional resistance to the movement of cross member 31 along the under surface of pivoted frame 12.

Even though this frictional resistance to movement of the parts may be increased more or less when the seat is occupied and the upholstery springs are further compressed, the resistance in no way interferes with efficient operation of the mechanism. The resistance is sufficient, however, together with the weight of a person's body, to maintain the parts in any adjusted position without any effort on the part of the occupant.

The interengagement of cross member 31 and grooves 22, 22 provides for an initial, relatively high resistance to movement of the chair back 23 from its normal, upright position of Fig. 1. This prevents the chair back from moving out of the sitting position as soon as the occupant brings his weight against the back, even though he desired to remain in the sitting position.

To move the back from the sitting position, the occupant exerts sufficient pressure against the back with the upper part of his body to force member 31 out of grooves 22, 22 and onto the main, flat surfaces of members 13, 13.

This initial rearward movement of the back and other subsequent rearward movements are facilitated by the natural raising of the portion of the person's body occupying the rear of the seat, when he pushes the upper portion of his body against the chair back. This partially removes the weight of the person's body from the rear upholstery springs 20. Consequently the compression under which these springs is held is reduced, and with it, the frictional resistance to movement between cross member 31 and seat frame 12.

When the back is moved to any desired position in the manner described, it remains so adjusted as long as the position of the occupant's body is unchanged. However, as soon as the occupant raises his body, spring 32 causes the chair back to automatically follow the position of the occupant's back. When he leaves the chair, the back immediately returns to the sitting position of Fig. 1.

Attention is called to the fact that in my adjustable chair construction the conventional seat upholstery springs 20 perform a dual function. That is, they not only support the upholstery seat 8, but provide the spring means necessary for operation of the adjustable back. The bottom frame 12, which is not unlike the ordinary seat bottom frame, also serves a dual purpose, that of sup-

porting upholstery springs 20 and functioning as a part of the friction device for the adjustable back.

The mechanism whereby the back of the chair may be adjusted is extremely simple in construction and operation and requires the use of a minimum of extra parts.

Various changes may be made in the details of the chair, since it is not intended that the invention be restricted to the construction shown, except as it may be limited by the appended claims.

What is claimed is:

1. In a chair, the combination of a body frame; a stationary seat attached to said frame; a movable seat bottom mounted in the frame; spring means between the seat and the seat bottom; a back pivoted in the body frame; and means on the back below its pivot for slidably supporting a portion of the seat bottom.

2. In a chair, the combination of a body frame; a stationary, flexible seat attached to said frame; a seat frame pivoted in the body frame; spring means interposed between the seat and the seat frame; a back pivoted in the chair frame and having a portion thereof extending below its pivot for slidably supporting a free end of the seat frame; and spring means for normally maintaining the chair back in an upright position.

3. In a chair, the combination of a body frame; a flexible seat secured about its edges to the body frame; a seat frame pivotally mounted at its front edge in the body frame; coil springs located between the seat and the seat frame; a back pivotally mounted intermediate its ends in the body frame; a cross member mounted on the back below its pivot and slidably supporting the free end of the seat frame; and spring means for maintaining the back in a normal, upright position.

4. In a chair, the combination of a body frame; a stationary seat attached to said frame; a seat frame mounted in the body frame; spring means between the seat frame and the seat; a back pivoted in the body frame and normally disposed in an upright position; means on the back below its pivot for slidably supporting a portion of the seat frame; and means for causing relatively high, initial resistance to movement of the back from its normal position.

5. In a chair, the combination of a body frame; a stationary seat attached to said frame; a seat frame pivotally mounted at its front edge in the body frame; springs located between the seat and the seat frame; a back pivotally mounted intermediate its ends in the body frame for movement between sitting and reclining positions; a cross bar mounted on the lower end of the back below its pivot and slidably supporting the free end of the seat frame, said seat frame being provided with a depression on its under side;

and spring means connecting the back and the chair frame for normally maintaining the back in sitting position with the cross bar in said depression.

6. The combination in a chair of a body frame; a stationary seat attached to said frame; a movable member mounted in the frame beneath the seat; spring means interposed between the seat and said member to oppose movement of the latter towards the seat; a back pivoted in the body frame; and means on the back below its pivot for slidably engaging said movable member and actuating it in opposition to said spring means upon movement of the back towards reclining position.

7. The combination in a chair of a body frame; a stationary seat attached to said frame; a seat frame pivotally mounted in the body frame; spring means between the seat and the seat frame opposing upward movement of the free end of the seat frame; a back pivotally mounted intermediate its ends in the body frame and having a portion thereof below its pivot slidably engaging said free end of the seat frame to support said end and to elevate it upon rearward swinging movement of the upper portion of the back; and spring means for maintaining the back in a normal, upright position.

8. In a chair, the combination of a body frame; a flexible seat attached directly to said frame; spring means mounted on the frame and resiliently supporting the seat; a back pivotally mounted on the frame for movement between sitting and reclining positions; and means, including slidably-engaging parts, interposed between the back and the spring means, whereby movement of the back towards reclining position is resisted by said spring means.

In testimony whereof I have signed my name to this specification.

ISAAC C. DECKER.
